(57) **CLAIM**

The ornamental design for an electrical connector, as shown and described.

DESCRIPTION

FIG. 1 is a front, top, and right-side perspective view of an electrical connector;

FIG. 2 is a front, top, left-side perspective view of the electrical connector shown in FIG. 1;

FIG. 3 is a top, front, left-side perspective view of the electrical connector shown in FIG. 1;

FIG. 4 is a top plan view of the electrical connector shown in FIG. 1;

FIG. 5 is a bottom plan view of the electrical connector shown in FIG. 1;

FIG. 6 is a right-side elevational view of the electrical connector shown in FIG. 1;

FIG. 7 is a left-side elevational view of the electrical connector shown in FIG. 1;

FIG. 8 is a front-side elevational view of the electrical connector shown in FIG. 1;

FIG. 9 is a rear-side elevational view of the electrical connector shown in FIG. 1;

FIG. 10 is an enlarged partial view of section 10 of the electrical connector shown in FIG. 1; and,

FIG. 11 is an enlarged partial view of section 11 of the electrical connector shown in FIG. 1.

In the drawings, the broken lines show portions of an electrical connector that form no part of the claim. The surface shading illustrated in the drawings is provided merely to highlight the contour of the design; it is not intended to be illustrative of texture or gloss.
